SCOTLAND.

BROADSIDE-FIRING TORPEDO-TUBE.

1,100,676.

Specification of Letters Patent. Patented June 16, 1914.

Application filed March 13, 1914. Serial No. 824,436.

To all whom it may concern:

Be it known that we, MARLEY FOTHERINGHAM HAY, a subject of the King of Great Britain and Ireland, and FERDINAND GUHRAUER, a subject of the King of Hungary, residents of Dumbarton, Scotland, have invented certain new and useful Improvements in Broadside-Firing Torpedo-Tubes, of which the following is the specification.

10 Hitherto submerged broadside firing torpedo tubes have not been very successful when fired from ships under way, because the flow of water past the emerging torpedo tends to break it off or to jam it in 15 the mouth of the tube.

The invention has for its object to obviate this disability.

According to the invention there is vertically pivoted near the muzzle of the torpedo tube proper and within it a secondary tube within which lies the torpedo or the forward portion of it. The tube proper is of such shape that the secondary tube may swing within it on its pivot through a horizontal arc adequate for the purpose herein-after set forth. Thus at a determined point in its travel, the emerging torpedo leaving the tube proper is wholly borne by the secondary tube, which, being free to swing 25 upon its pivot, allows the emerging torpedo to accommodate itself to the flow of water by swinging out of the direct path of aim—to which of course it subsequently returns under the action of its gyroscope.

30 In carrying out this invention according to an illustrative example, the forward end of the tube proper is so attached by a spherical joint (also arranged to prevent leakage) to a frame that it may be trained through a horizontal arc. This frame is hinged to the ship's side for the purpose of permitting the tube to be swung around so that it may be loaded in a narrow ship, and is locked to it when in the firing position by means of a 35 lock ring. The tube is supported substantially in known manner beneath its center of gravity on a carriage having rollers engaging an arc of rail on the ship's deck. The embrasure is externally closed by a hinged or sliding door operated from within the vessel. The secondary tube is pivoted within the tube proper on vertical trunnion pivots coaxial with the spherical joint between tube proper and frame. Means are 40 provided for admitting and discharging

water to and from the tubes. Any convenient means of firing may be used—it being however essential that such should embody a device whereby the gyroscope of the torpedo is started a certain predeterminate time before the actual firing takes place.

In operation the tube is loaded from the forward, or after end, the embrasure being first closed, and the hinged frame unlocked and with the tube swung around upon its hinge so that the tube may be loaded with a torpedo, which without this arrangement would not be possible in a narrow vessel, as the space required for loading is at least twice the length of the torpedo.

In order that the invention and the manner of performing the same may be properly understood, there is hereunto appended a sheet of explanatory drawings in which—

Figure 1 is a sectional elevation and Fig. 2 a plan of the improved torpedo tube, while Fig. 3 is a transverse section on the line a—a Fig. 1 showing the locking ring.

As shown in the drawings, the torpedo tube 1 has within it a secondary tube 2 carried by vertical pivots 4 and within which lies the forward end of the torpedo 3. The torpedo tube 1 is widened for the length of the secondary tube 2, so that the latter has a certain amount of freedom to swing about 80 its pivots 4 for the purpose herein-after set forth. To prevent leakage past the pivots 4, a ball and socket joint 32, 33 is provided in the mouth of the tube 1.

To allow of the torpedo being trained through a horizontal arc, the forward end of the tube 1 is in the form of a ball 5 working in socket pieces within frames 6, 7, the latter of which has a stuffing box 8 to prevent leakage into the ship. The frame 7 is hinged at 9 to the ship's side for the purpose of permitting the tube to be swung around so that it may be loaded in a narrow ship and is locked to it when in the firing position by means of a locking ring 10, the frame 100 7 and the locking ring 10 being so shaped as to form a bayonet joint. The ring 10 is screwed internally on to a frame 11, and is actuated by means of a worm 12 working on a rack 13 on its outer circumference. The frame 11 extends inwardly to form an embrasure 14 through which the torpedo is fired, and which is closed by means of a door 15 hinged on a shaft 16 which is operated by means of a worm 17 engaging a 110

quadrant 18 on one end of the shaft 16. The tube 1 is supported substantially beneath its center of gravity on a carriage 19 having wheels 21 running on an arc of rail 22 on the ship's deck, the arc of rail being struck from a pin 20 to which the carriage 19 is pivoted. The tube 1 is borne in this carriage by wheels 23 which allows limited freedom of movement to the tube, so that it 10 may accommodate itself to the arc of rail when swinging around the hinge 9. A valve 24 is provided to admit water to or discharge it from the tube 1, while the air escapes by means of air tubes 25, 26 and 15 valves 27, 28.

The after part of the tube 1 is surrounded by a casing 29 which is charged with compressed air by means of a valve 30. The compressed air is admitted into the tube 1 20 to fire the torpedo by means of a usual firing valve 31, the valves 24, 27, 28, 30 and 31 being operated by hand or by any other suitable known means.

In order to insure that the gyroscope of 25 the torpedo is started a certain predeterminate time before the latter is fired, there is provided a firing rod 32 having on it two fingers 33, 34, so positioned on the rod 32 that when it is actuated the finger 33 first 30 engages a trigger 35, which in turn draws back a catch 36 far enough to start the gyroscope. Further movement of the rod 32 brings the finger 34 into contact with a series 35 of toggle links 37 which on being actuated release a catch 38 and thus the torpedo. Immediately after the catch is released the rod 32 may also actuate the firing valve 31, in known manner to fire the torpedo.

In operation, to load the torpedo, the embrasure 14 in the frame 11 is first closed by 40 the door 15 on the shaft 16 operated as hereinbefore described. The locking ring 10 is then operated by means of the worm 12 and rack 13 until the bayonet joint is unlocked. 45 Then the frame 7 and the torpedo tube 1 are swung around the hinge 9 until the latter is in the loading position, that is, lengthwise of the ship, and it is then loaded from either the forward or after end. The tube 50 1 and the frame 7 are again swung around the hinge 9 and locked in the firing position by means of the locking ring 10. The tube is then flooded with water through the valve 24, the air escaping by the valves 27, 28, and 55 the door 15 swung around the shaft 16 by means of the worm 17 and the quadrant 18 into its open position. The casing 29 around the after part of the tube is then charged with compressed air through the 60 valve 30. The tube is then ready to be fired and is swung around the arc of rail 22 on the ship's deck into the aiming position. To fire the torpedo, the rod 32 is actuated until the finger 33 engages the trigger 35, which 65 in turn draws back the catch 36 far enough

to start the gyroscope. Further movement of the rod 32 brings the finger 34 into contact with the toggle links 37, which on being operated release the catch 38 and thus the torpedo. The firing valve 31 may be 70 opened at the same time by the firing rod, and the compressed air from the casing 29 enters the tube 1 and discharges the torpedo. The torpedo as it emerges travels in the line of the tube 1 so long as it remains in the narrow portion of the tube 1, but immediately it is wholly borne by the secondary tube 2 in the wider portion of that tube 1, it is free to swing with the secondary tube 2 about the pivots 4 and so 75 accommodate itself to the pressure of the water flowing past the mouth of the tube by swinging out of the direct path of aim—to which, of course, it subsequently returns under the action of its gyroscope. After 80 firing, the door 15 is closed and the water in the tube 1 drained away by means of the valve 24, after which the locking ring 10 may be unfastened and the tube 1 may be again swung into the loading position, all 85 as hereinbefore described.

What we claim is:

1. In a broadside firing torpedo tube of the type in which the forward end of the tube is so attached to the ship's side that it 90 may be trained through a horizontal arc, a secondary tube pivoted near the muzzle of and lying within the torpedo tube, the torpedo tube being widened for the length of the secondary tube so that the latter may 100 swing within it about its pivots through a horizontal arc.

2. In a broadside firing torpedo tube of the type in which the forward end of the tube is so attached to the ship's side that it 105 may be trained through a horizontal arc, a secondary tube within the torpedo tube, the latter being widened for the length of the secondary tube, a ball and socket joint in the mouth of the torpedo tube and vertical 110 trunnion pivots for the secondary tube in this joint and coaxial therewith.

3. In a broadside firing torpedo tube of the type in which the forward end of the tube is so attached to the ship's side that it may 115 be trained through a horizontal arc, a secondary tube within the torpedo tube, the latter being widened for the length of the secondary tube, means for pivoting the secondary tube near the muzzle of and within 120 the torpedo tube, and means for hinging the torpedo tube on and locking it to the ship's side.

4. In a broadside firing torpedo tube of the type in which the forward end of the 125 tube is so attached to the ship's side that it may be trained through a horizontal arc, a secondary tube within the torpedo tube, the latter being widened for the length of the secondary tube, a ball and socket joint in 130

the mouth of the torpedo tube and vertical trunnion pivots for the secondary tube in this joint and coaxial therewith, and means for hinging the torpedo tube on and locking it to the ship's side.

- 5 5. In a broadside firing torpedo tube of the type in which the forward end of the tube is so attached to the ship's side that it may be trained through a horizontal arc, 10 a secondary tube within the torpedo tube, the latter being widened for the length of the secondary tube, means for pivoting the secondary tube near the muzzle of and within the torpedo tube, a frame on the torpedo tube, a pivot on the ship's side to which the frame is attached, a second frame secured on the ship's side, a lock ring screwed internally on to the second frame and making a bayonet joint with the first frame, and 15 20 worm gearing operating the lock ring.

6. In a broadside firing torpedo tube of the type in which the forward end of the tube is so attached to the ship's side that it may be trained through a horizontal arc, a 25 secondary tube within the torpedo tube, the latter being widened for the length of the secondary tube, means for pivoting the secondary tube near the muzzle of and within the torpedo tube, means for hinging the 30 torpedo tube on and locking it to the ship's side, and means for firing the torpedo and for starting the gyroscope a certain predetermined time before actual firing takes place.

- 35 7. In a broadside firing torpedo tube of the type in which the forward end of the tube is so attached to the ship's side that it may be trained through a horizontal arc, a secondary tube within the torpedo tube, the latter being widened for the length of the secondary tube, a ball and socket joint in the mouth of the torpedo tube and vertical trunnion pivots for the secondary tube in this joint and coaxial therewith, means for hinging the torpedo tube on and locking it to the 40 45 ship's side, and means for firing the torpedo and for starting the gyroscope a certain pre-

determinate time before actual firing takes place.

8. In a broadside firing torpedo tube of the type in which the forward end of the tube is so attached to the ship's side that it may be trained through a horizontal arc, a secondary tube within the torpedo tube, the latter being widened for the length of the secondary tube, means for pivoting the secondary tube near the muzzle of and within the torpedo tube, a frame on the torpedo tube, a pivot on the ship's side to which the frame is attached, a second frame secured on the ship's side, a lock ring screwed internally on to the second frame and making a bayonet joint with the first frame, and worm gearing operating the lock ring, and means for firing the torpedo and for starting the gyroscope a certain predetermined time before actual firing takes place.

9. In a broadside firing torpedo tube of the type in which the forward end of the tube is so attached to the ship's side that it may be trained through a horizontal arc, a secondary tube within the torpedo tube, the latter being widened for the length of the secondary tube, means for pivoting the secondary tube near the muzzle of and within the torpedo tube, and means for hinging the torpedo tube on and locking it to the ship's side, a casing surrounding the after part of the torpedo tube, a valve through which the casing is charged with compressed air, a firing valve admitting the compressed air from the casing to the tube, a firing rod and mechanism operated thereby, by which the torpedo is released and fired, and by which the gyroscope is started a certain predetermined time before actual firing takes place.

In testimony whereof we have signed our names to this specification, in the presence of two subscribing witnesses.
